UNITED STATES PATENT OFFICE.

LEROY L. PERRINE, OF BEDFORD, INDIANA.

PLAYING-CARDS.

1,246,152.

Specification of Letters Patent. Patented Nov. 13, 1917.

Application filed May 31, 1916. Serial No. 100,815.

To all whom it may concern:

Be it known that I, LEROY L. PERRINE, a citizen of the United States, residing at Bedford, in the county of Lawrence and State 5 of Indiana, have invented new and useful Improvements in Playing-Cards, of which the following is a specification.

My invention relates to game cards, and particularly to a pack of cards designed for 10 the purpose of affording interest, amusement and instruction.

The object of the invention is to provide a pack of cards which may be employed for the playing of games, and also for instruction in number work, such as arithmetic, and may, therefore, be used by those of all ages with manifold profit in point of interest, 15 amusement and educational benefit.

In the accompanying drawing, showing 20 for illustrative purposes, certain means for carrying my invention into practical effect,

Figure 1 is a view showing generally and diagrammatically a pack of cards embodying characteristic features of the invention; 25 Figs. 2, 3 and 4 show obverse and reverse views of selected cards of certain suits of the pack;

Figs. 5, 6 and 7 are obverse views of cards 30 illustrating adaptations of the invention; and

Figs. 8 and 9 are similar views of irregular or joker cards.

In carrying my invention into practice, I provide a pack of cards consisting of any 35 desired number of suits, and of a prescribed number of cards in each suit, together with or including supplemental card or cards having certain arbitrary values, as hereinafter fully described. For purposes of illustration, it may be considered that the pack consists of twelve suits of cards, of twelve cards to the first suit, and of progressively diminishing numbers throughout the remaining suits, together with other supplemental or 45 arbitrarily valued cards, if desired. For reasons which will hereinafter appear all of the suits following the first diminish successively in number by one in regular sequence, throughout the series, the second 50 suit numbering eleven cards, the third ten cards, the fourth nine cards, and so on to the last (the twelfth) suit, which numbers but one (a single) card only.

The cards of the different suits are provided with indicia for presenting certain arithmetical problems to be solved, in addition

to which the cards are preferably and suitably provided with the products or answers to the respective problems. In the present instance I have shown in Figs. 60 2, 3 and 4 the obverse and reverse faces, respectively, of certain cards belonging to certain suits, Figs. 2 and 3 showing the first and last cards of the first suit, and Fig. 4 the first card of the second suit.

The cards as illustrated in Figs. 1 to 4, inclusive, are printed in a suitable color or colors to present problems or examples in multiplication, and it will be observed that the card shown in Fig. 2, which is the first 70 card of the first suit, bears upon its obverse face *a* the problem or example " 1×1 ", disposed at different ends of the card in reverse relationship, so as to show alike with either end of the card uppermost, and upon its reverse face the number "1", expressing the product or answer to the problem. It will also be observed that the obverse and reverse faces of the final card of the first suit shown in Fig. 3 bear in a similar manner the 80 problem or example " 1×12 " and the product or answer "12". From this it may be understood that the first set of cards of the pack will constitute the first section of problems of the multiplication table, denoting problems of the numeral "1" as the multiplicand multiplied by consecutive multiplier numerals ranging from one to twelve, inclusive, while the cards of the second suit will bear in consecutive order problems using the numeral "2" as an exponent multiplicand for multiplication by multiplier numerals from two to twelve, inclusive, and so on throughout the suits or series of cards up to the final or twelfth suit, which consists of a single card, 95 as shown in Fig. 1, bearing upon its obverse face the problem " 12×12 " and upon its reverse face the answer thereto.

By this mode of presenting the examples or problems each suit or series of cards will, 100 in addition to numbering one less than the preceding suit, have its examples or problems begin with its own number, in its order of arrangement in the suit, both as multiplier and multiplicand, as, for instance, " 3×3 ", 105 " 5×5 ", " 8×8 ", respectively, for the initial cards of the third, fifth and eighth suits. This is due to the fact that it is unnecessary to repeat the same example reversed in different suits (as " 3×4 " in the third suit 110 would be equivalent to " 4×3 " in the fourth suit), and hence by the novel notation set

forth but seventy-eight cards instead of one hundred and forty-four (exclusive of supplementary cards) need be used to express all the wide range of sums in the multiplication table. The subject indicia is accordingly reduced to the simplest possible degree with obvious advantages in point of bulk of cards used in the pack, expense of manufacture, convenience of use and understanding, and other important considerations.

Thus it will be observed that the pack of cards may consist in general of a set of suits or series of cards bearing arithmetical problems, shown for example as multiplication problems, the different cards of the different suits bearing different problems throughout a plurality or series of multiplier divisions, while the cards of each suit or series bear different problems within the multiplier division covered thereby, and hence that by the use of cards bearing the stated indicia different multiplication problems will be expressed for display and use and the answers thereto given. In a like manner the cards may be made to present other arithmetical problems in addition, subtraction and division, as illustrated by certain cards shown by way of exemplification in Figs. 5, 6 and 7, which, in practice, will 25 embody all essential features of the cards shown in Figs. 2 to 4, inclusive, each bearing upon its face the proper figures and signs expressing the problems and upon its back the answer to such problems. The 30 object in supplying the product or the answer to the problem on each card upon the back of the card, for concealment until such side of the card is exposed, is to enable all 35 doubts to be settled as to the proper answer to a problem in the playing of the game or 40 solving of the problems by children of lower grades or those not proficient in mathematics.

In addition to any number of regular or 45 exponent cards in a pack, I provide, as hereinbefore stated, other cards having arbitrary indications or values, two of which are shown, for purposes of exemplification, in Figs. 8 and 9. It will be observed that these 50 cards bear exponents expressing irregular or non-solvable problems, that appearing on the card shown in Fig. 8 indicating in subtraction an impossible problem, as "5-7", while that appearing upon the card shown 55 in Fig. 9 shows a similar impossible problem, namely, "6÷7". These cards, which may be removed when the pack is used by small children or the lower grades for instruction work, serve the function of jokers 60 and are intended for use in playing a game for which the cards are particularly adapted, and which I call "Arithmo", which cards are given out under certain conditions to the first player at the start of a game. Each of 65 these joker or irregular cards is intended to

have a certain arbitrary value, which may, for example, be equal to ten or more regular cards for counting purposes.

It will of course be understood that the cards may be employed by an instructor in 70 teaching arithmetic to children and others, and may be used by disposing different cards throughout the different divisions or series in turn to present different examples to be solved, the answers to which may be 75 found upon the backs of the cards in case of dispute or for certainty of decision. By the use of different packs of cards with problems in different arithmetical processes or divisions, as multiplication, addition, 80 subtraction and division, it will also be obvious that instructions in lower mathematics may be given in an interesting and entertaining manner. Of course, the cards may bear other matter more or less related 85 to the subject, and the size of the pack, as well as the number of suits in each pack, may vary as desired or as may be considered most advisable for instruction or amusement purposes.

In playing with the cards the game "Arithmo" or any similar game, the players gather about a table and any number of persons within reasonable limits may play the game. One of these, preferably the best 90 in addition, subtraction, multiplication or division, may be appointed the dealer, who takes the pack of cards in one hand, with the exponent side of each card up, that is, with the sides bearing the problems or examples facing in the same direction and disposed so as to be brought into general view, the dealer holding the cards so that the obverse faces thereof will be wholly concealed.

To start the game the dealer calls "Arithmo" and throws one card upon the table in view of all the players, the obverse face up. The player who first calls the correct answer to the problem or example presented by this card takes the card and the dealer immediately throws down another card. With children and others who may not be proficient, the dealer, in case of doubt, may refer to the back of the cards for the 105 correct answer. Should two call the correct answer so nearly together that the dealer cannot decide to whom the card belongs, it is put on the bottom of the pack to be thrown or dealt later. When the cards are 110 all out of the dealer's hands, the game is over and the player holding the greatest number of cards wins. As before stated, the irregular or joker cards have arbitrary values, and of these cards there may be one 115 or more in each pack, and such cards may be given to the first player calling "Arithmo" or solving the problem at the start of the game and at other predetermined periods or portions throughout the 120 125 130

game, if so desired. These irregular or joker cards, therefore, may be material factors in deciding a closely played game and in addition to their arbitrary values add zest in 5 affording increased interest and amusement.

As will be apparent, the game is not only instructive and causes great interest but is amusing to a high degree, and the cards having value both for instruction work simply, 10 as well as instruction and amusement, increase the range of usefulness of the invention to a material degree. It will of course be understood that in playing a game or instructing those advanced in arithmetic the 15 cards of the different sets or divisions may be mixed.

Having thus described my invention, I claim:

A pack of cards comprising a designated 20 series of suits of cards bearing arithmetical

examples upon their obverse faces and the answers thereto upon their reverse faces, the cards of the different suits bearing different index figures of progressively increasing values, the cards of the respective suits also 25 progressively decreasing in number by one in regular sequence throughout the series, the examples upon the cards of the same suit differing from each other in arithmetical value but having the same index figure as 30 a basis for calculation, and the examples upon the cards of the different suits progressively increasing in arithmetical values throughout the several suits.

In testimony whereof I affix my signature 35 in presence of two witnesses.

LEROY L. PERRINE.
